GOLF GAME BOARD

Vincent Crupi, 230 Greenwich St., Reading, Pa.

Filed May 13, 1964, Ser. No. 79,974

Term of patent 14 years

(Cl. D34—5)

FIG. 2 is an edge view thereof.

I claim:

The ornamental design for a golf game board, substantially as shown.
